UNITED STATES PATENT OFFICE.

ARTHUR W. WALKER, OF MALDEN, MASSACHUSETTS.

DESIGN FOR A STOVE OR RANGE.

SPECIFICATION forming part of Design No. 24,802, dated October 29, 1895.

Application filed September 11, 1894. Serial No. 522,756. Term of patent 14 years.

To all whom it may concern:

Be it known that I, ARTHUR W. WALKER, a citizen of the United States, residing at Malden, in the county of Middlesex, State of Massachusetts, have invented a new and original Design for a Stove or Range, of which the following is a specification, reference being had to the accompanying drawing, forming part thereof.

The drawing represents in perspective a stove or range, showing my design.

The parts of the stove or range are shown as mounted on an elevated base *a*, of generally rectangular form, having slightly-convex sides *a'* and scroll-like ornaments *a''* at the front corners. An upright body *b* surrounds the base at the front, each side of the body forming a panel *b'*, and an oblong door *b''* is located at the front of the body between the drop-door *b'''* and the ash-doors *b''''* and extended across the tops of the latter. The body *b* terminates in a top section *b''''*, rearwardly extended beyond the body and over the base *a*, a detached column *c* rising from each rear corner of the base *a* to the top extension above it, while an arch plate *c'* tops the space between the detached column *c* and side panels *b'* below the top extension or section *b''''*. The top section has lateral horizontal extensions *b''''* thereon. Upon the top section *b''''* is erected a columnar support *d*, bearing upon it an elevated oven *e*.

A convex scalloped base *d'* surrounds the foot of the support, upon the front of which is an oval panel *d''*, surrounded by a conventionalized leaf-border *d''''*, lateral wings *f* extending in a vertical plane from the columnar support *d* between the top *b''''* and elevated oven *e* and having irregularly - curved outlines.

The oven *e* has, as herein shown, a convexed lower portion *e'* and a slightly-flaring top *e''*, connected by end panels, as *e''''*, and swinging doors *e'''''*, forming the front.

The leading feature of the design consists in the base, the upright body surmounting it at the front, the rearwardly-extended top section on the body, the columnar support erected upon the extension, the elevated oven borne upon the support, and the detached columns between the top extension and the rear of the base.

I claim—

The design for a stove or range, substantially as shown and described.

In testimony whereof I have signed my name to this specification in the presence of two subscribing witnesses.

ARTHUR W. WALKER.
